ve the upper end of the pencil
is designated by the number 22. 110

and useful improvements in Pencils, of
which the following is a specification.
This invention relates to a pencil equipped
with propelling mechanism interiorly of its
body, and operable by means exteriorly
thereof, for advancing into operative posi-
tion a lead at one end, and an eraser at the
other. In many respects the present pencil
follows the construction already disclosed in
15 certain patents of Charles R. Keenan granted
March 22, 1921, as Nos. 1,372,296 and
1,373,354; it exhibits, however, certain im-
provements which have to do particularly
with a magazine within the pencil for the
20 accommodation of reserve leads. It is to
be understood, therefore, that the present
pencil embodies a number of features
claimed in the applications aforesaid, as
well as certain other improvements to which
25 specific reference will hereinafter be made.

In the accompanying drawing, an exam-
plification of this invention is shown in the
manner following:

Figure 1 is a longitudinal section through
30 a tubular pencil body, certain of the inter-
ior parts being shown in elevation;

Fig. 2 is a similar view, enlarged, through
the upper portion of the pencil;

Fig. 3 is a transverse section taken on
35 line 3—3 of Fig. 2;

Fig. 4 is an elevation of the magazine
member shown in Fig. 2; and

Fig. 5 is an enlarged detail in longitu-
40 dinal section of the upper end of the pencil
showing a bushing arranged above the mag-
azine member.

In the use that is herein made of the terms
“upper” and “lower”, it is to be under-
stood that I am referring to the pencil as it
45 is pointed in use—that is, with the eraser
end up, and the writing end down.

In Fig. 1 the pencil body, designated as
A, is provided with a lower end 10 which
terminates bluntly in the form of a trun-
50 cated cone. In the construction shown, this
body may be produced from metal in tubu-
lar formation so as to provide a casing
within which are accommodated the operat-
ing parts, as well as reserve leads. Ar-
55 ranged centrally within the body is a tube

yond the rad

nated as 21,

within the p

also lies abo

body which

The central tube 11, however, extends slightly beyond the threaded end of the member and is flared outwardly as at 23 in overlying relation thereto so as to fixedly secure the magazine member in place. A combined pencil head and magazine closure D is also provided which, as shown, consists of an eraser sleeve 24 and a rotatable collar 25 which may be formed internally with an annular groove wherein is received a split ring 32 engaging also within a complementary groove 33 formed exteriorly of a bushing 34 having extended walls 35 which connect fast with the eraser sleeve. By some such means as this a freely rotatable connection may be provided between the two parts of the head. A second bushing 26 is also carried fast in the lower portion of the collar and is internally threaded to connect to the upper end 21 of the magazine member. When arranged in place upon the pencil, as shown in Figs. 1 and 5, the walls of the collar are aligned with those of the casing by a projection 22^a of the bushing 26 which extends within the casing a short distance. Connected fast with the eraser sleeve is an operating sleeve 27 disposed within the tube 11 and formed with screw threads for engaging with a threaded plunger 28 adapted for non-rotatable travel within the pencil tube, the plunger being advanced or retracted with rotation of the tube 11 through the medium of the eraser sleeve, to advance a lead or an eraser in a manner similar to that disclosed in the Keeran application already referred to.

The connection between the pencil head and body may be modified, if desired, to take the construction shown in Fig. 5. I have here represented the upper end of the magazine member as terminating slightly below the upper end 22 of the pencil body. Over the member is arranged a bushing 30 secured non-rotatably to the tube 11, as by sweating or solder, and the tube extremity is further spun out as at 31 to overlie this bushing so as to retain the same in place. Through the medium of threads formed exteriorly on the bushing a connection is established with the collar bushing 26 so that the head D may be detachably secured to the pencil.

According to the invention that I have herein described the parts which form the magazine of this pencil may be very accurately and expeditiously produced. Their assembly into the pencil may be accomplished with ease and precision. The construction is such as to provide for a number of compartments each of which may accommodate a desired number of reserve leads in such a manner as to prevent undue motion therein. No shoulder or other element projects interiorly from the casing at its upper end to interfere in the least with

the removal or insertion of these leads. Furthermore, it will be noted that the connection between the pencil head and body is one which may be very readily disestablished so as to permit a single lead to be removed for purpose of insertion within the central tube 11 wherein propulsion is effected. 70

I claim:

1. A pencil having a hollow casing for its body, a tube arranged longitudinally therewithin in spaced relation to the body walls, a plate disposed transversely within the intervening space to form a bottom for a reserve lead magazine, a threaded closure for the magazine at its upper end, and means for securing the closure over the upper end of the pencil comprising a threaded part associated with the tube which is adapted to engage with the closure, there being a portion of the tube outwardly extended to overlie the end of the part which is associated therewith, substantially as described. 75 80 85

2. A pencil having a hollow casing for its body, a tube arranged longitudinally therewithin, a magazine member surrounding the tube and provided with walls extending towards the casing, a bushing surrounding the tube above the magazine member, the tube end being outwardly extended to overlie the bushing to thereby lock the bushing and magazine member within the pencil, and means forming a closure for the magazine adapted for detachable connection with the bushing, substantially as described. 90 95 100

3. A pencil having a hollow casing for its body, a tube arranged longitudinally therewithin, a magazine member arranged to provide walls extending radially between the tube and casing, the upper ends of said walls terminating short of the upper end of the tube, a bushing surrounding the tube and presenting one end to the magazine member and its other end adjacent the tube end, means projecting laterally from the tube end to overlie the bushing to lock the same in place, and means adapted for attachment to the bushing forming a closure for the magazine, substantially as described. 105 110 115

4. A pencil having a hollow casing for its body, a tube arranged longitudinally therewithin, a magazine member arranged to provide walls extending radially between the tube and casing, the upper ends of said walls terminating short of the upper end of the tube, a bushing surrounding the tube and presenting one end to the magazine member and its other end adjacent the tube end, and means adapted for attachment to the bushing forming a closure for the magazine, substantially as described. 120 125

5. A pencil having a hollow casing for its body, a tube arranged longitudinally therewithin and in spaced relation with the walls thereof, there being a reserve lead 130

magazine surrounding said tube, a closure for the magazine comprising a head adapted for connection with the pencil, and means for aligning the head with the casing, substantially as described.

6. A pencil having a hollow casing for its body, a tube arranged longitudinally therewithin and in spaced relation with the walls thereof, there being a reserve lead 10 magazine surrounding said tube, a closure for the magazine comprising a head adapted for connection with the pencil, and means independent of the connecting means for aligning the head with the casing, substantially as described.

7. A pencil having a hollow casing for its body, a tube arranged axially and im- movably therewithin in spaced relation to the walls thereof and adapted to contain lead propelling mechanism, a magazine 20 member fixedly surrounding the tube and consisting of a hub and a plurality of par- tions extending radially therefrom, and a closure for the magazine comprising a head adapted to be removably attached to the 25 upper end of the pencil and to be opera- tively connected with the lead propelling mechanism, substantially as described.

HUGO S. HASSELQUIST.
